UNITED STATES PATENT OFFICE.

JOHN L. JONES, OF SAVANNAH, GEORGIA.

SAW FILING AND GAUGING DEVICE.

Application filed December 12, 1924. Serial No. 755,565.

This invention relates to a saw filing device, the general object of the invention being to provide adjustable means for automatically holding the file in a certain position so that all the teeth of a saw can be filed to the same pitch.

Another object of the invention is to so arrange the parts that the device can be adjusted to file the teeth at any desired pitch.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a perspective view showing the invention in use.

Figure 2 is a plan view of the device.

Figure 3 is a longitudinal sectional view.

Figure 4 is an end view with the file in section.

In these views, 1 indicates the body of the file holder which is provided with a socket to receive the chucks 2 for engaging a file which is shown at A, the chucks being contracted by the sleeve 3. These parts are of the usual or any desired construction.

A handle 4 is rotatably mounted on the shank 5 of the body 1, said handle being provided with a sleeve 6 through which the shank passes, the parts being held together by the set screw 7. A collar 8 is rotatably mounted on a part of the body 1 and has a threaded socket 9 therein for receiving the threaded end of a weight 10 which tends to hold the collar in a certain position on the body. The collar is held in adjusted position on the body by the threaded sleeve 11 on the body which clamps the collar between itself and a part of the body.

A scale 12 is carried by the collar and a marker 13 is carried by a part of the body for permitting the collar to be adjusted to the desired extent on the body. Then by screwing the sleeve 11 against the collar the

collar will be held in its adjusted position. This scale and marker will permit the parts to be adjusted to give the file the proper position to cut the teeth at the desired pitch. The device is held with the handle in one hand and the fingers of the other hand holding the tip of the file. The weight 10 will cause the body and the file to move relatively to the handle until the weight is in its lowest position, which will be the position for which the file is set to give the teeth of the saw the desired pitch. Thus with this device all the teeth will be given the same pitch and they may be given any desired pitch by adjusting the parts of the device accurately and without guessing at the pitch.

The weight 10 may be provided with an opening 10' so that the weight can be used as a plumb bob by attaching a string to it by means of this passage.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A filing device comprising a holder, a collar rotatably mounted on a part of the handle, a threaded socket on the collar, a weight having threaded engagement with the socket, a nut for holding the collar in adjusted position on the body, file holding means associated with the body and a handle rotatably connected with the body.

2. A filing device comprising a handle, a collar rotatably mounted on a part of the handle, a threaded socket on the collar, a weight having threaded engagement with the socket, a graduated scale on the exterior of the collar, a handle rotatably connected with the body, a marker carried by the handle and adapted to cooperate with the scale, a nut for holding the collar in adjusted position on the body and file holding means associated with the body.

In testimony whereof I affix my signature.

JOHN L. JONES.
